FOLDING RACK

Filed Feb. 4, 1928

2 Sheets-Sheet 2

INVENTOR:

ABRAHAM S. KIRSHNER,

BY

Heiderling & Gould ATTORNEYS.

UNITED STATES PATENT OFFICE.

ABRAHAM S. KIRSHNER, OF PHILADELPHIA, PENNSYLVANIA.

FOLDING RACK.

Application filed February 4, 1928. Serial No. 251,790.

My invention relates to a new and useful folding rack which may be used for supporting a variety of household articles such as towels, clothes, wash rags, and similar articles, either for the purposes of drying or pending use.

Under present housing conditions it is desirable to economize space in small kitchens, kitchenettes, bath rooms or the like, and a support for articles that are only used occasionally which can be folded or disposed in an out of the way position as against the wall while such articles are not in use is obviously useful and advantageous.

It is the object of my invention to produce a folding rack which can be horizontally positioned for supporting towels and similar articles in a handy, accessible position while in use and which can be folded into an out of the way position or against the wall while such articles are not in use, thus effecting a substantial economy in space and presenting a neat and tidy appearance.

Folding towel racks and similar devices have heretofore been suggested, all of which, however, are rather complicated, unwieldy and expensive to manufacture and produce. It is therefore a further object of my invention to produce a folding rack which is of a simple, durable and inexpensive construction, comprising but two metallic members devoid of springs and complicated parts, and one which can be easily and effectively applied to a wall or other support, without moving the same to any extent.

To the above ends, my invention consists of a supporting bracket having a lower, forwardly projecting angular portion and an upper eye, and being adapted to be secured to a support, in conjunction with a longitudinal supporting arm, a U-shaped link passing through said eye and pivotally secured to said arm, and transverse rods carried by said bar in suitable spaced relation to each other, one of said rods passing through terminal eyes in said U-shaped link.

My invention further consists of various other novel features of construction and advantage all as will be hereinafter described and claimed.

For the purpose of illustrating my invention I have shown in the accompanying drawings one form thereof which is at pres-

ent preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the accompanying drawings,

Figure 1, represents a perspective view of a folding rack embodying my invention, the same being shown in operative horizontal position.

Figure 2, represents on an enlarged scale a fragmentary top plan view of the same.

Figure 3, represents on an enlarged scale, a fragmentary side elevation of the folding rack and its adjuncts, the rack being shown in folded position in dotted lines.

Figs. 4, 5 and 6 represent a modification of my invention.

Referring to the drawings, in which like reference characters indicate like parts, 1 designates a support such as a wall, door or the like, to which is secured the supporting bracket 2 by the screws or the like 3. The bracket 2 is provided with the upper eye 4 and the lower angular portion 5. 6 designates a supporting arm, which is provided with the transverse rods or bars 7 on which an article such as a towel, wash rag or the like may be supported. 8 designates a U-shaped link, the rear portion 9 of which passes through the eye 4, and is provided with the limbs 10 having the terminal eyes 11 through which passes the rearmost of the rods or bars 7 thereby forming a pivotal support as will be understood from Figs. 1, 2, and 3. The end of the lower angular portion or tongue 5 is recessed as at 12 which recess engages the upper, rear edge 13 of the arm 6, when the latter is in the horizontal or operative position.

When it is desired to use the folding rack of my invention, it is merely necessary to pull or draw the arm 6 outwardly from the position seen dotted in Fig. 3 into the horizontal or upwardly inclined position until the rear edge 13 thereof clears the angular lower portion of the bracket 2. The free end of the arm 6 is then adjusted so that the upper rear portion 13 thereof is

seated in the recess 12, the rear end 14 of the arm 6 then abutting against the wall as seen in Fig. 3, thus maintaining the arm 6 in a substantially horizontal or slightly upwardly inclined position.

When it is desired to fold up the rack, it is merely necessary to pull the arm 6 outwardly until the rear end thereof clears the end of the tongue or angular portion 5 and then lower the arm into a vertical pendant position, substantially parallel with the wall 1, as shown in dotted lines in Fig. 3.

It will thus be seen that the folding rack of my novel construction is composed of the supporting bracket 2, the connecting link 8 and the arm 6 through which passes the transverse bars or rods on which a towel or similar articles may be supported.

It will further be seen that my novel folding rack may be brought into the horizontal operative position, or may be folded against a wall or other support by a single simple movement of the arm to and fro. It will also be apparent that my novel folding rack can be manufactured and assembled at a minimum cost, due to the simplicity and minimum number of its parts.

In the modified form illustrated in Figs. 4, 5 and 6 I employ, in lieu of the bracket 2, a bracket 15 which has the integral, lower, forwardly projecting tongue or flange 16 and which is adapted to be secured to a wall or other support by the screws or other fastening devices 3. The bracket 15 is provided with the bifurcated head 17 which has a through aperture 18. Similarly in lieu of the U-shaped link 8, I employ a solid one-piece link 19 the upper end of which is secured in the bifurcated head 17 by means of the bolt or pin 20 as will be understood from Figs. 4, 5 and 6. In lieu of the supporting arm 6, I employ a supporting arm 21 which is split or bifurcated at its rear end as at 22, for the reception of the free end of the link 19, as will be understood from Figs. 5 and 6. The arm 21 is provided with a plurality of transverse rods or bars 23, the rearmost one of which passes through registering apertures in the limbs of the rear bifurcated portion of the arm 21 and the free end of the link 19 pivotally to secure said arm to said link. The principle and operation of this modification of my invention is the same as that described in connection with Figs. 1, 2 and 3. Thus when it is desired to bring the supporting arm 21 into the horizontal, operative position, it is merely necessary to position the rear upper edge 24 of the arm 21 beneath and in engagement with the lug or tongue 16, which, in conjunction with the link 19, will maintain the arm 21 in a horizontal operative position, as shown in full lines in Fig. 4. If it is desired to fold the arm 21 into and out of the way position, it is merely necessary

to exert a forward pull on the arm 21, until the rear edge 24 thereof clears the lug 16, whereupon the arm 21 can be dropped into a vertical position, substantially parallel with the wall or support 1 and will occupy the position shown in dotted lines in Fig. 4.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention what I claim as new and desire to secure by Letters Patent, is:—

1. In a device of the character stated, a thin, flat, one-piece bracket, an eye formed integral with said bracket at its top and extended transversely thereof, a tongue formed integral with said bracket and projected forwardly from the bottom thereof in a transverse manner, an inverted substantially U-shaped link pivotally mounted in said eye, and having terminal eyes, a supporting arm, and means for pivotally securing the free ends of said link to the rear portion of said arm, whereby the latter may be swung into a vertical inoperative position or into a horizontal operative position at will.

2. In a device of the character stated, a thin, flat, one-piece bracket, an eye formed integral with said bracket at its top and extended transversely thereof, a tongue formed integral with said bracket and projected forwardly from the bottom thereof in a transverse manner, a substantially U-shaped link pivotally mounted in said eye, a supporting arm, cross bars carried thereby, and means for pivotally securing the free ends of said link to the rear portion of said arm, whereby the latter may be swung into a vertical inoperative position, or into a horizontal operative position, said arm being maintained in its unfolded position by engagement with the underside of said tongue.

3. In a device of the character stated, a support, a thin, flat, one-piece bracket adapted to be secured to said support and having an upper transverse eye and a lower forwardly projecting transverse tongue, with a transverse recess therein, a supporting arm, transverse cross bars arranged to support various articles carried thereby and a connecting link pivotally mounted in said eye, said link having a terminal eye, through which the rearmost transverse bar passes, whereby said arm may be swung into a vertical inoperative position or into a horizontal operative position at will, said recess in said tongue engaging the upper edge of said arm for maintaining the latter in unfolded

position, the rear end of said arm also abutting against said support when in the latter position.

4. In a device of the character stated, a thin, flat, one-piece bracket having an upper transverse eye and a lower abutment, said eyes and abutment being formed integral with said bracket, an arm provided with a

plurality of transversely extended rods which pierce said arm so as to extend upon opposite sides thereof, and a link the upper end of which has pivotal relation with the bracket eye and the lower end of which is penetrated by the rearmost of said rods. 10

ABRAHAM S. KIRSHNER.
